ICE CUBE TRAY OR SIMILAR ARTICLE

Charles O. Bliss, Los Angeles, Calif.

Application February 15, 1955, Serial No. 34,517

Term of patent 14 years

(Cl. D67—3)

FIG. 1

FIG. 2

Fig. 1 is a perspective view of an ice cube tray showing my new design; and

Fig. 2 is a side view thereof.

The both sides of the tray have the same appearance.

The characteristic feature of my design for the ice cube tray disclosed resides in the handle member having the configuration shown.

I claim:

The ornamental design for an ice cube tray or similar article, substantially as shown and described.
